J. SECHOWSKI

ELECTRIC FURNACE

Filed Aug. 17, 1923

Jerome Sechowski

INVENTOR.

BY *Alfred O'Brien*
ATTORNEYS.

UNITED STATES PATENT OFFICE.

JEROME SECHOWSKI, OF NOTRE DAME, INDIANA.

ELECTRIC FURNACE.

Application filed August 17, 1923. Serial No. 657,899.

To all whom it may concern:

Be it known that I, JEROME SECHOWSKI, a citizen of the United States, residing at Notre Dame, in the county of St. Joseph and State of Indiana, have invented certain new and useful Improvements in Electric Furnaces, of which the following is a specification.

In carrying out the present invention it is my privilege to provide an electric furnace wherein a building may be properly heated without the necessity of employing a coal furnace in conjunction with the heating system thereof which type of furnaces are very disagreeable in view of the fact that they must necessarily be fired from time to time and ashes must be removed which occasions considerable dust and a great expenditure of time, labor and money.

The primary object of my invention is to provide such an electric furnace that is extremely simple of construction and one that may be installed and operated at minimum cost the nature of the same being such that the furnace may be disassembled for renewal or repair purposes.

With the above and other objects in view as the nature of the invention will be better understood, the same comprises the novel form, combination and arrangement of parts set forth in the following specification, shown in the accompanying drawings and claimed.

In the drawings wherein like reference characters indicate corresponding parts throughout the several views,

Figure 1 is a vertical detail cross section of my improved furnace,

Figure 2 is a transverse section taken substantially upon the line 2—2 of Figure 1,

Figure 3 is an enlarged cross sectional view through one of the heating coils employed in conjunction with the furnace, and

Figure 4 is an enlarged fragmentary elevation partly in cross section through a certain portion of the furnace for more clearly disclosing the securing means between different walls of the furnace.

Now having particular reference to the drawings, my novel furnace embodies a casting made up of sheet metal side walls 5, front and rear walls 6, a bottom wall 7 and a top wall 8. The side and front and rear walls are preferably integrally joined together the top and bottom walls thereof be-

ing flanged for engagement within said side and front and rear walls and being secured thereto through the medium of a bolt and nut connection 9, Fig. 4.

Secured in any desirable manner within the casing and pendant from the top wall thereof is a partition 10 that terminates adjacent the bottom wall 7 of the casing for dividing the same into what may be termed compartments designated 11 and 12 respectively the compartment 11 being of relatively less dimensions than said compartment 12.

Within said compartment 12 and secured to said partition 10 and the adjacent side wall 5 of the casing are inwardly extending inverted pan shaped partitions or baffles 13 the length of the same being less than the length of said compartments, each alternate one of the partitions being carried by said partition 10, the remainder thereof being carried by the adjacent side wall 5 of said casing.

Extending longitudinally beneath each of said partitions 13 are spaced rods 14 the opposite ends thereof engaging through openings in the flanges of the partition as shown in Fig. 3. Surrounding each of these rods 14 is a tube 15 of a suitable insulating material while surrounding each of these tubes is an uninsulated copper wire coil 16 the coils upon each of said rods being electrically connected to each other while the coils carried by each of the partitions are also electrically connected as more clearly shown in Fig. 1.

The top wall of the casing above said compartment 7 is provided with an inlet opening 17 over which is arranged the outlet of a fan casing 18 there being disposed within this casing a blower 19 that is rotated at high speed through the medium of a desirable form of electric motor 20 there being necessarily a driving connection between the armature shaft of said motor and the shaft 100 of said blower 19.

The casing 18 is manifestly provided with an air inlet pipe 21.

Within the compartment 12 wherein there is arranged the before mentioned electric coils is a water tank 22 that is in communication with a filler spout 23 that extends outwardly within the side wall of the furnace casing whereby water may be placed within the tank it being obvious that the 110

heated air will naturally become moistened a slight degree due to the presence of this water.

Above said compartment 12 the top wall 8 of the casing is provided with a suitable number of openings 24 over which are arranged the inlet ends of air conveying pipes 25 these pipes extending to radiators disposed at desirable points within the building.

The motor 20 is in open circuit with the house current through the medium of a switch located at a convenient point within the building as is also the heating element 15 arranged within the compartment 12 and whenever it is desired to operate the furnace these switches are obviously closed. A rotation of the motor 20 will cause a rotation of the blower 19 for consequently drawing air through the pipe 21 and forcing the same downwardly within the compartment 11 in the direction of the arrows this air passing beneath the partition 10 and then going in a circuitous path between the different partitions 13 that carry the heating coils this air being obviously heated during the course of its travel from the bottom to the top of the casing.

The specific operation together with the numerous advantages of an electric furnace of this character will be at once obvious to those skilled in the art and even though I have herein set forth the most practical embodiment of the invention with which I am at the present time familiar it is nevertheless to be understood that minor changes may be made within the invention without departing from the spirit and scope of the appended claims.

Having thus described my invention what I claim as new and desire to secure by Letters Patent is:—

1. In an electric furnace, a casing divided internally by a vertical partition into separate compartments, said partition terminating in spaced relation from the bottom of the casing to afford communication between

the compartments, the top of said casing being provided above one of said compartments with an opening, air circulating means mounted on said casing and in communication with said openings for driving air through said compartment and into the remaining compartments, a plurality of horizontally disposed baffles arranged in the last named compartments in staggered relation, said baffles being mounted alternately upon said partition and one of the walls of the last named compartment, said baffles being of a width equal to the compartments and of a length less than the length of the compartment whereby to afford a restricted and torsioned passage for the incoming air, and electric heating elements disposed beneath said baffles and arranged in transversely spaced rows.

2. In an electric furnace for domestic purposes, a casing divided by a vertical partition into small and large compartments, said partition terminating in spaced relation from the bottom of the casing to afford communication between the compartments, the casing being provided in its top at a point above the small compartment with an opening, air circulating means mounted upon said casing for driving the air through said opening and then through said small compartment into the large compartment, a plurality of inverted pan shaped baffle plates mounted in said last named compartments alternately upon said partition and one of the casing walls, said baffle plates being of a width equal to the width of the compartment and of a length less than the length of the compartment whereby to provide a tortuous and restricted passage for the air, a plurality of bolts mounted beneath each plate in a transverse row, sleeves of insulation surround said bolts, and electricity conducting wire coiled around said sleeves.

In testimony whereof I affix my signature.

JEROME SECHOWSKI.
